UNITED STATES PATENT OFFICE.

CHARLES T. MELVIN, OF AURORA, ILLINOIS, ASSIGNOR, BY MESNE ASSIGNMENTS, TO STANDARD GAS EQUIPMENT CORPORATION OF MARYLAND.

INSULATING MEANS.

Application filed April 28, 1925. Serial No. 26,562.

My invention relates to thermal insulated lining for receptacles such as, ovens, refrigerators, etc., and its novelty resides in the construction, adaptation and method of using the parts.

It is an important desideratum in linings of this character that they be of such construction, that will afford permanent maximum insulation and be readily assembled or dissembled, without the use of special tools.

In an embodiment of the invention herein, I have shown an adaptation of the lining to an electric oven. Here the lining is shown as comprising a set of six K. D. sections of welded steel tank construction, from which the air has been exhausted, and the tank sealed, so as to maintain a continuous vacuum. The top and bottom sections are alike. 20 The rear section is provided with two openings for terminal plugs, and one vent hole adapted to communicate with a vent pipe in the oven receptacle. The rear section is further provided with four spring catch lugs 25 embossed on the inside surface, the purpose of which will be hereinafter described.

The two side sections are identical, each being provided with rack cleats, which are stamped from a sheet of metal of same size 30 as the section and preferably spot-welded thereto. The front or door section is adapted to be bolted to the door frame of the receptacle.

In the drawings:

35 Fig. 1 is a dissembled perspective view of the six sections comprising the receptacle lining,

Fig. 2 is a horizontal section through an oven receptacle, showing the sections in position and as indicated on the line 2-2 in Fig. 3, and looking in the direction of the arrows. One of the sides is indicated in broken lines showing the method of swinging same into place,

45 Fig. 3 is a vertical longitudinal section of the receptacle with sections in place, and

Fig. 4 is a vertical transverse section as indicated on the line 4-4 in Fig. 3 and looking in the direction of the arrows.

50 Similar reference characters refer to similar parts throughout the several views of the drawings.

The set of linings comprise a top section 10, a bottom section 11, two side sections 12 and 13 respectively, a rear section 14 and a

front or door section 15. The top and bottom sections are alike and are formed from two pieces of sheet metal 10^a, 10^b and 11^a and 11^b respectively, each sheet being provided with a peripheral flange 10^c and 10^d and 11^c 60 and 11^d respectively, adapted to fit one within the other so as to form chambers 10^m and 11^m respectively and to be hermetically joined by suitable means such as roll or acetylene welding.

65 The two side sections 12 and 13 respectively are alike and resemble top and bottom sections 10 and 11 in that they are made from two pieces of sheet metal 12^a, 12^b and 13^a, 13^b, respectively, each sheet being provided with a flange 12^c, 12^d and 13^c, 13^d respectively and a chamber 12^m and 13^m respectively. In addition each of the sections 12 and 13 has secured thereto a stamped metal sheet 12^e and 13^e provided with 70 75 standing flanges 12^f and 13^f respectively, constituting rack cleats, for the support of racks within the oven.

75 The rear section 14 is formed of a plate 14^a and provided with a peripheral flange 14^b. This plate 14^a is provided with two oppositely disposed openings 14^c and 14^d for terminal plugs, and a vent opening 14^e, adjacent the upper left hand corner. Four spring lugs are provided and adapted to 80 engage the inner ends of the side sections 12 and 13 respectively when the oven lining is assembled. An insulated portion 14^g (Fig. 3) is secured to the rear of the plate 14^a as by spot-welding. This portion is of smaller 85 area and when centrally located on the plate 14^a, there is formed a channel around the edge of the plate. In this channel are located the openings 14^c and 14^d, vent 14^e and the spring lugs 14^f. The portion 14^g is 90 formed from two pieces of sheet metal 14^h and 14ⁱ, each sheet being provided with a peripheral flange 14^j and 14^k respectively and adapted to fit one within the other so as to form a hermetically sealed chamber 95 14^m as heretofore described.

100 A front or door section 15, comprises a flat plate 15^a provided with bolt holes 15^b, one in each corner. Centrally located on the rear of the plate 15^a is a rectangular cup shaped member 15^c, provided with a peripheral flange 15^d which contacts with the plate 15^a and is welded thereto to form a hermetically sealed chamber 15^m. Each section having been made, the air is removed therefrom 110

and sealed so as to provide as nearly as complete a vacuum as possible.

The sections are now ready to be assembled within the receptacle or electric oven 16

5 as herein illustrated. This structure may be of box-like form open at one end. The rear wall is provided with inlets 16^c and 16^d corresponding to the openings 14^c and 14^d in the rear section 14. There may be also a 10 vent opening 16^e corresponding to the vent 14^e in the rear section. The front or open end 16^b of the receptacle is provided with an inturned peripheral flange 16^f the purpose of which will be hereinafter described.

15 A reinforcing or finishing ring 16^g is secured to the front wall 16^b around the opening, and to this ring 16^g is hinged a door frame 17 provided with the usual ornamental plate 17^a.

20 To assemble the lining within the receptacle proceed as follows:—First the bottom section 11 is placed in the receptacle, then the top 10, both being located under the flange 16^f of the receptacle, which serves to 25 hold the sections in place. While the top 10 is being held up by one hand and the flange 16^f, the rear section 14 can be pushed into the rear of the receptacle 16 and against the rear wall 16^a. One of the side sections

30 12 may now be placed behind the flange 16^f and swung into position, passing the spring lugs 14^f in the rear section 14. (Clearly shown in broken lines and arrow in Fig. 2.) The other side section 13 may be placed in 35 position in the same way.

The door section 15 is then secured to the door frame 17 by bolts 17^b which pass through bolt holes 15^b in the door section. This completes the assembly and all of the 40 sections are securely locked in place, the interior presenting a trim appearance, free from projections or wide cracks.

45 By reversing the foregoing procedure, the oven lining may be easily and quickly disassembled and therefore any part replaceable, should it lose its vacuum or become impaired of its usefulness in any other manner.

What I claim and desire to cover by Letters Patent is as follows:

50 1. In an oven of the kind described, a vacuum shell arranged to fit the top supported by a flange, a vacuum shell to fit the rear, spring lugs in said rear shell, vacuum shells to fit the sides and bottom, the said shells supported by a flange and said spring lugs.

55 2. In an oven of the kind described, a vacuum shell arranged to fit the top supported by a flange, a vacuum shell to fit the rear, spring lugs in said rear shell, vacuum

shells to fit the sides and bottom, the said shells supported by a flange and said spring lugs, the side shells having rack cleats to support racks in the oven.

60 3. In an oven of the kind described, a vacuum shell arranged to fit the top supported by a flange, a vacuum shell to fit the rear, spring lugs in said rear shell, vacuum shells to fit the sides and bottom, the said shells supported by a flange and said spring lugs, and a door with a vacuum shell mounted thereon and adapted to close the front wall of said oven.

65 4. In an oven of the kind described, a vacuum shell arranged to fit the top supported by a flange, a vacuum shell to fit the rear, spring lugs in said rear shell, vacuum shells to fit the sides and bottom, the said shells supported by a flange and said spring lugs, the side shells having rack cleats to support racks in the oven, and a door with a vacuum shell mounted thereon and adapted to close the front wall of said oven.

70 5. In an oven of the kind described, vacuum shells movably mounted therein, supporting means, recesses in said shells and said shells joined to the walls of the said oven and forming dead air spaces between the walls of said oven and said shells.

75 6. In an oven of the kind described vacuum shells mounted on the bottom, top, sides and rear wall of said oven, recesses in said shells and said recesses mounted adjoining the walls of said oven to form dead air spaces.

80 7. In an oven of the kind described vacuum shell units co-extensive with the top, bottom, sides and rear wall of said oven, a recess in each of the said units formed by a peripheral flange supporting means and said vacuum shells mounted adjacent the interior of said oven to form dead air spaces.

85 8. In an oven of the kind described, insulating means comprising both vacuum shells and dead air spaces, the latter formed by recesses in said shells and supporting means.

90 9. In an oven of the kind described, insulating means comprising both vacuum shells and dead air spaces, the latter formed by recesses in said shells and supporting means comprising in part said vacuum shells.

95 10. In an oven of the kind described, insulating means comprising both vacuum shells and dead air spaces, the latter formed by recesses in said shells and supporting means, and said shells movably mounted in said oven.

110 In witness whereof, I have hereunto set my hand this 21st day of April, 1925.

CHARLES T. MELVIN.
